UNITED STATES PATENT OFFICE.

JOHN W. HASBURG, OF CHICAGO, ILLINOIS.

PAINT-PACKAGE.

1,366,654.

Specification of Letters Patent. Patented Jan. 25, 1921.

Application filed June 14, 1920. Serial No. 388,735.

To all whom it may concern:

Be it known that I, JOHN W. HASBURG, a citizen of the United States, residing at Chicago, county of Cook, State of Illinois, have 5 invented a certain new and useful Improvement in Paint-Packages, and declare the following to be a full, clear, and exact description of the same, such as will enable others skilled in the art to which it pertains to 10 make and use the same, reference being had to the accompanying drawings, which form a part of this specification.

My invention has for its object to produce a cheap, simple and novel package for 15 inclosing a mastic product, such as gold paint, deposited upon a palette of glass, which will permit the employment of a simple carton while affording adequate protection to the packaged product against dust 20 or other foreign matter and against disturbance on the palette, and which will permit the package to be made with a minimum expenditure of labor and the contents to be placed in and taken out of the package without 25 danger of disturbing the product on its palette.

In carrying out my invention I place over the covered palette a follower having a part extending from one edge underneath the 30 palette and to and beyond the opposite edge, so as to form a composite body of parts which, when grasped at one edge, will have its parts firmly held together against accidental displacement and be placed in or removed from a carton without danger of injuring the product which it is the purpose of the package to protect. This principle of temporarily uniting a plurality of overlying elements, while especially useful in 35 the particular art to which I have heretofore referred, may also be employed for other purposes and therefore, viewed in one of its aspects, my invention may be said to have for its object to produce a simple and novel 40 grouping of individual elements so as to permit them to be handled without danger of accidental relative displacement in forming or undoing a package.

The various features of novelty whereby 45 my invention is characterized will herein-after be pointed out with particularity in the claims; but, for a full understanding of my invention and of its objects and advantages, reference may be had to the following 50 detailed description taken in connection with the accompanying drawing, wherein:

Figure 1 is a top plan view of a palette carrying a quantity of gold paint in the form of a thin wafer, with its cover and follower, ready to be placed in a carton; 60

Fig. 2 is a section on line 2—2 of Fig. 1; and

Fig. 3 is a vertical section through the completed package, including the carton.

Referring to the drawing, 1 represents a 65 palette which is preferably in the form of a square plate of glass. Upon this palette is a thin disk or wafer of paint smaller in diameter than the width or length of the palette. Above the palette is a cover, preferably in the form of a sheet of celluloid resting at its marginal portions, as indicated at 3, on the palette outside of the periphery of the paint disk and dished upwardly, as indicated at 4, above the paint. 70 Above the cover is a follower, substantially the same size as the palette, this member comprising a flat portion, 5, adapted to rest on the flat marginal portion, 3, of the cover, and having a central opening, 6, large 80 enough to permit the dished central portion of the cover to project through the same. At the edges of the follower are upwardly-projecting flanges, 7. The follower may be made out of any suitable material, 85 being preferably a sheet of cardboard cut to the proper shape and scored so as to permit the flanges to be bent up therefrom. To one side or end of the follower is attached a tongue, 8, of flexible material, preferably 90 thin tough paper; this tongue being extended long enough to extend across the bottom of the palette and project a considerable distance beyond the side or edge opposite to the point of attachment of the tongue. 95

When a package is to be made, the loaded palette, cover and follower are assembled one on the other as illustrated in Figs. 1 and 2 and then, by grasping the projecting end of the tongue and the adjacent portion 100 of the follower between the thumb and finger, the three independent elements are temporarily tied together so that they will not accidentally become displaced relatively to each other and thus cause the paint to be 105 disturbed. While holding the assembled palette, cover and follower in the manner just described, they are inserted into the open end of a flat carton, 9, made just large enough to receive them and having a depth 110 such that the upper edges of the flanges, 7, on the follower will engage with the top

wall of the carton and cause the follower to press the marginal portions of the cover tightly against the palette. The open end of the carton is preferably provided with a 5 flap, 10, long enough to extend across the open end and permit a portion thereof to project into the carton in contact with the under side of the top wall of the latter. When the contents of the carton are placed 10 in the same, the tongue, 8, projects out of the open end of the carton so that, when the closing flap is folded inwardly, the tongue is bent or folded upwardly against the adjacent flange of the follower. Then, when 15 the carton is opened, the projecting end of the tongue is exposed and may be grasped for the purpose of pulling out the contents of the carton. After the contents have been partially withdrawn from the carton, the 20 tongue and the overlying portion of the follower are grasped between the thumb and the finger so as to hold the palette, cover and the follower tied together until it is desired to release them.

25 If desired, the tongue may be made long enough so that it may be bent or folded over the inwardly-extending section of the closing flap of the carton and thence to the exterior of the carton, as indicated in Fig. 3, 30 between the closing flap and the top wall of the carton. The carton may be opened by grasping the projecting end of the tongue and pulling on it; the result being first the 35 pulling out of the closing flap and then, if the pull is continued, the withdrawal or partial withdrawal of the contents.

While I have illustrated and described with particularity only a single preferred form of my invention, I do not desire to be 40 limited to the exact structural details thus illustrated and described; but intend to cover all forms and arrangements which come within the terms employed in the definitions of my invention constituting the 45 appended claims.

I claim:

1. In a package, a palette, a dished cover resting along its margins on the palette, a follower resting on the marginal portions 50 of said cover, and a tongue extending from one edge of said follower underneath the palette.

2. In a package, a plate, a cover overlying the plate, a follower overlying the cover, 55 and a part extending from one edge of the follower underneath the plate.

3. In a package, a plate, a cover overlying the plate, a follower overlying the cover, and a part extending from one edge of the 60 follower underneath the plate to and beyond the opposite edge.

4. A package comprising a plate, a cover overlying the plate, a follower overlying the cover, a part extending from one edge of the

follower underneath the plate to the opposite edge; a carton surrounding said plate, cover and follower and having an open end at the last mentioned edge; and a closure for the open end of the carton.

5. A package comprising a plate, a cover 70 overlying the plate, a follower overlying the cover, a part extending from one edge of the follower underneath the plate to and beyond the opposite edge; a carton surrounding said plate, cover and follower and 75 having an open end at the last mentioned edge; and a closure for the open end of the carton.

6. A package comprising a plate, a member 80 overlying the plate and having a part extending from one edge underneath the plate to the opposite edge; a carton surrounding said plate and said member and having an open end at the last mentioned edge; and a closure for the open end of said 85 carton.

7. A package comprising a plate, a member overlying the plate and having a flexible 90 part extending from one edge underneath the plate to and beyond the opposite edge; 95 a carton surrounding said plate and said member and having an open end at the last mentioned edge; said carton having at said open end a closing flap folded inwardly and holding the projecting end of said part bent 100 upwardly.

8. A package comprising a plate, a member overlying the plate and having a flexible part extending from one edge underneath the plate to and beyond the opposite edge; 100 a carton surrounding said plate and said member and having an open end at the last mentioned edge; said carton having at said open end a closing flap folded upwardly and inwardly; and the projecting end of the 105 aforesaid part being folded over the free edge of said flap and outwardly so as to project from the carton and permit the flap to be pulled out thereby and the plate and the said overlying member to be pulled out 110 of the carton.

9. A package comprising a palette, a dished cover overlying the palette and resting thereon at its marginal portions, a follower resting on said marginal portions of 115 the cover and having an opening through which the dished portion of the cover projects, upwardly-projecting flanges on said follower, a tongue extending from one edge of the follower underneath the palette to 120 and beyond the opposite edge; a carton surrounding the palette, cover and follower and having an open end at said edge; and a closure for the open end of said carton.

In testimony whereof, I sign this specification. 125

JOHN W. HASBURG.
